United States Patent Office

Des. 192,733
Patented May 8, 1962

192,733

CEILING TILE

Ramon R. McNeil, 152 Riverview,
International Falls, Minn.

Filed Sept. 14, 1960, Ser. No. 62,136

Term of patent 14 years

(Cl. D18—2)

FIG. 2

FIG. 1

FIG. 3

FIGURE 1 is a top plan view of a ceiling tile showing my design;

FIGURE 2 is an edge view of said ceiling tile; and

FIGURE 3 is a partial sectional view taken along line 3—3 of FIGURE 1.

I claim:

The ornamental design for a ceiling tile, substantially as shown.

References Cited in the file of this patent

UNITED STATES PATENTS

D. 188,491 Green _____ Oct. 2, 1960

OTHER REFERENCES

Architectural Record, October 1958, page 38, New Idea No. 3.